FORM SHAPING DEVICE FOR WOOD-
WORKING MACHINESJohn Oliver Creek and Walter Wood, Hamilton,
Ontario, Canada

Application March 24, 1933, Serial No. 662,487

2 Claims. (Cl. 144—145)

Our invention relates to improvements in the production of the shaper forms as are used in machine wood working for the production of a plurality of similar pieces of work from a master pattern.

In general practice the wood worker takes the master pattern, clamps it upon a piece of board called the shaper form and then manually cuts away one edge of the shaper form board until it conforms with the outline of the side face of the master pattern positioned thereabove. This is a lengthy and tedious operation as the wood worker has to be particularly careful to make the edge of the shaper form of the exact formation of the side of the master pattern. When the wood worker has completed this operation, which is done by hand, the shaper form is then ready for use in reproduction work, and in making the duplicate pieces of work he clamps a roughly formed piece of wood onto the shaper form in lieu of the master pattern and utilizes the formed edge of the shaper form as a guide in milling or shaping the face of the piece of wood in conformity therewith.

The object of our invention is to obviate hand work in forming the side edge of the shaper form board and to do this we have provided a guide member adapted to be used in conjunction with the rotary cutter of a spindle wood shaping machine wherein the face of the master pattern mounted upon the shaper form can be brought to bear against the guide whereby the cutter-head mills away the edge of the shaper form in conformity with the side face of the master pattern.

A still further and particular object of our invention is to provide our guide, which is of stationary vertical cylindrical form, of a height at least equal to the total face depth of the contacting side face of the master pattern, and another object of our invention is to adjustably secure the cylindrical guide upon a bracket which is adapted to be attached to the table of a wood shaping machine.

Another object of our invention is to furnish a ring member adapted to be adjustably secured upon the cylindrical guide for increasing the diameter thereof, which is necessary in certain types of reproduction work as shall be hereinafter explained.

Our invention consists of a guide of the character set forth all as hereinafter more particularly described and illustrated in the accompanying drawing in which:

Fig. 1 is a perspective view of a rotary cutter-head projecting upwardly from the face of a fragmentary portion of a shaper table in accordance with standard practice, the standard type of guide ring being shown in conjunction therewith.

Fig. 2 is a similar figure to Fig. 1 showing the

cutter-head partially lowered through the orifice in the table, our guide member being shown positioned thereabove.

Fig. 3 is a perspective view of a shaper form, showing the master pattern clamped thereon, before the edge of the shaper form is cut away to conform with the side face of the master pattern.

Fig. 4 is a perspective view of a roughly shaped piece of wood before having its side face shaped to conform with the side face of the master pattern.

Fig. 5 is a vertical cross sectional view through our cylindrical guide member showing a detachable ring positioned on the lower portion thereof for use for certain classes of work, and

Fig. 6 is a side elevational view of the cutter-head as shown in Fig. 1 wherein the blades thereof are inclined for cutting a sloping face.

Like characters of reference indicate corresponding parts in the different views in the drawing.

The standard type of spindle wood shaping machine comprises a flat table top 1 upon which the work to be machined is placed together with a vertical cutter-head 2 projecting upwardly through an orifice 3 in the top, the cutter-head being adjustable in height, that is, it can be fully raised as shown in Fig. 1 or moved downwardly as shown in Figs. 2 and 5. The standard type of machine is also provided with a ring 4 adapted to be contained within the orifice 3 and having an upwardly extending guide collar 5 of the same outer face diameter as the diameter of the path of rotation of the edges of the cutter blades 6 carried upon the head 2. The work to be cut or milled is clamped upon a shaper form as illustrated in Fig. 3 and the shaper form moved across the surface of the table until the knives of the rotating cutter-head engage the work carried thereon. In Fig. 3 we have shown the cut away or formed edge 7 of the shaper form, in the dotted lines, and it will be understood that when such edge 7 is brought to bear against the guide collar 5 that the cutter-head will mill the face of the piece of work into conformity with the outline of the edge 7.

As explained in the preamble of our specification, the object of our invention is to provide a means whereby the edge 7 of the shaper form can be machine cut in conformity with the side face of the master pattern.

To achieve this object we provide a cylindrical guide member 8 of a height not less than the height of the cutting face of the milling cutter head and of the same diameter as the diameter of the guide collar 5 and therefore also of the same diameter as the diameter of the cutting path of the blades 6, and by the provision of an upwardly extending bracket 9 mount the cylindrical guide 8 above the lowered cutter-head.

The cylindrical guide member 8 can be secured to the bracket 9 in any suitable manner, but as it is desirable to have the cylinder 8 adjustable in height, we provide the construction shown in Figs. 2 and 5 wherein the lower end 10 of the bracket is bolted or clamped to the table and the upper end 11 formed with a vertical slot 12 for the reception of a lock screw 13 which extends through the slot and is threaded into the orifice 14 in the cylinder 8. By loosening the screw 13 the cylinder can be moved relatively to the bracket through the distance of length of the slot and if it is desired to secure a further adjustment we furnish a second threaded orifice 15 into which the locking screw 13 can be fitted. As the face of the bracket in contact with the face of the cylinder 8 is curved to conform with the curvature of the cylinder face a single screw 13 will rigidly retain the cylinder in place.

In using our guide a master pattern such as indicated at 16 is clamped upon the shaper form board 17 in any suitable manner such as by clamps 18, the clamps being of any suitable type to rigidly hold the master pattern in place against longitudinal movement and also to retain the master pattern against rear movement when pressed against the cylinder 8. The lower end of the cylinder 8 is positioned above the face of the table 1 a slightly greater distance than the thickness of the board 17 and the cutter-head 2 is moved upwardly to a position just underneath the bottom face of the cylinder 8. The machine is then started to rotate the cutter-head and the edge portion 20 of the shaper form board 17 is pressed against the rotating knives 6 until the face 21 of the master pattern makes contact with the face of the cylinder 8 and as the board 17 is moved to and fro the edge portion 20 will be cut away in conformity with the face 21 of the master pattern, as shown by the dotted lines in Fig. 3. It will be understood that the top cylinder 8 is at least as high as the highest point of the face 21 of the master pattern. When the edge of the shaped form has been cut the master pattern is removed and the shaper form is then ready for the reception of a rough cut piece of the material to be shaped, such as indicated by the numeral 30 in Fig. 4.

The bracket 9 and cylinder 8 are removed from the table and the filler ring 22 also removed. The spindle 23 carrying the cutter-head is then moved to the uppermost position above the face of the table and the cutter-head moved therefrom. The ring 4 with its guide collar 5 is then inserted into the orifice 3 in lieu of the ring 22 and the cutter-head 2 repositioned upon the spindle above the guide collar 5 as illustrated in Fig. 1. The machine is then ready for reproduction work, wherein the face of the work clamped upon the shaper form is brought into contact with the cutter-head, and the formed edge 7 of the shaper form into contact with the guide collar 5.

In the shaping of certain pieces of work wherein one or more of the faces is sloped upwardly and inwardly, as for example the piece of work 24 illustrated in Fig. 6, in which the side 25 is inclined, we furnish a ring 26 which is adapted to be slid over the cylinder 8 and locked in its adjusted position by a set screw 27 threaded therethrough to engage the cylinder. The ring is so positioned upon the cylinder that it is engaged by the inclined face 28 of the master pattern 29 when the

edge of the shaper form is being cut. If the ring were not provided, only the lower edge of the inclined face of the master pattern would engage the cylinder, and this, of course, would possibly injure the master pattern, render the operation hazardous to the wood worker, as well as making it nearly impossible to achieve a true reproduction of the face outline upon the edge of the shaper form.

In the cutting of the pieces of work from the master pattern, the blades 6 are adjusted upon the cutter-head so that they are angularly inclined at the same inclination as the face 28 of the master pattern, as shown in Fig. 6, so that the correct face inclination is achieved as well as the correct outline from the formed edge of the shaper form.

From the foregoing description it will be seen that we have provided a simple and yet very useful device by means of which the edges of shaper forms can be machine cut in accordance with a master pattern, and although we have shown our guide 8 of complete cylindrical form it is to be understood that it is not necessary to have the guide in the form of a complete cylinder as long as there is sufficient face area to give adequate contact when the shaper form is being cut, and therefore we do not limit our invention to the specific construction shown and described but may make such changes and alterations as we may at any time deem necessary without departing from the spirit of our invention as set forth in the appended claims.

What we claim as our invention is:

1. A wood working machine for finishing an irregularly shaped rough piece comprising a table top having an opening therethrough, a stationary guide detachably mounted above said opening, a rotary cutter passing through said opening and extending above the top adjacent the bottom of the guide whereby said guide and cutter will cooperate with an irregularly shaped master pattern and a board to produce a shaper form, an auxiliary attachment comprising a guide collar and a cutter thereabove replaceable in said opening upon removal of the guide and first mentioned cutter, said collar and cutter of the attachment operable to reproduce a face on said irregularly shaped rough piece from the shaper form.

2. A wood working machine for finishing an irregularly shaped rough piece comprising a flat table top having an opening therethrough, a substantially cylindrical guide having its lower edge spaced from the table and positioned above said opening, a rotary milling cutter passing through the opening into position adjacent the lower edge of the guide whereby said guide and cutter will cooperate with an irregularly shaped master pattern and a board to produce a shaper form, an annular guide collar of a height corresponding to the thickness of the board adapted to be positioned in and extending above said opening upon removal of the cylindrical guide said cutter being adapted to be repositioned with its lower edge adjacent the upper edge of the annular guide whereby said irregularly shaped rough piece carried by the shaper form may be brought into position adjacent the annular collar and the cutter in its last named position and a face thereof fashioned to the contour of the form.
